[57] ABSTRACT

A forming system for concrete floor and roof decks is provided having all parts standardized, separable and reusable, including shoring, displacement domes or flat panels and half cradle and side panels, all constructed and related to enable quick virtually tool-free erection as well as removal for reuse. The displacement domes or flat panel forms are readily removable before the shoring if desired to reduce the between-use intervals. Convenient latch lock connections are provided for rapid erection and dismantling of components.

FORMING SYSTEM FOR CONCRETE FLOOR AND ROOF DECKS

This invention relates to improvements in the making of poured concrete structures, and is more particularly concerned with a new and improved forming system for concrete floor and roof decks in building construction.

Heretofore it has been common practice to erect by carpentry techniques shoring and forms for poured concrete floor and roof decks, necessitating use of a large amount of lumber which is generally discarded when the shoring and forms are torn down. This has been a costly and wasteful procedure both in materials and manpower. Even where displacement forms of the reusable metal pan type have been employed, the shoring has generally consisted of lumber erected by the usual carpentry practices.

While attempts have been made to replace at least part of the lumber structure by reusable members, we are not aware of any other systems which are not objectionable for one or more reasons such as depending largely on members that must be nailed or secured by screw type fasteners, special tools, limited utility, excessive cost not only of equipment but in labor, lack of interchangeability of parts, etc.

An important object of the present invention is to overcome the foregoing and other disadvantages, defects, inefficiencies, shortcomings and problems in prior methods and structures and to attain important advantages and improvements in and with the new framing system for concrete floors and roofs as will hereinafter become apparent.

Another object of the invention is to provide a new and improved system of the character indicated which will greatly facilitate the erection of poured concrete building structures.

A further object of the invention is to provide a new and improved forming system for concrete floors and roof decks and which can be quickly erected or dismantled largely without the use of tools and where tools are needed enabling the use of the simplest conventional tools.

Still another object of the invention is to provide a new and improved forming system of the character indicated including novel framing means.

Yet another object of the invention is to provide a new and improved forming system comprising novel form means.

A still further object of the invention is to provide a new and improved forming system including novel latch lock means for separably connectable parts.

A yet further object of the invention is to provide a new and improved forming system of the character indicated which is highly versatile to meet numerous and varied dimensional and attitude requirements, with built-in adjustment features in the assembly of separable, reusable components.

An additional object of the invention is to provide a new and improved forming system for efficient, economical, rapid, accurate, high quality concrete floor and roof deck constructions.

Other objects, features and advantages of the invention will be readily apparent from the following description of certain preferred embodiments thereof, taken in conjunction with the accompanying drawings, although variations and modifications may be effected

without departing from the spirit and scope of the novel concepts embodied in the disclosure, and in which:

FIG. 1 is a fragmentary isometric illustration of a system embodying features of the invention;

5 FIG. 2 is a side elevational view of the system of FIG. 1 including height extension and floor level jack means;

FIG. 3 is an enlarged side elevational view of the half cradle structure;

10 FIG. 4 is a back elevational view of the half cradle structure;

FIG. 5 is an enlarged representative fragmentary sectional view showing details of one of the latch lock connections severally employed in the system;

15 FIG. 6 is a fragmentary illustrative elevational view showing one of the form supports;

FIG. 7 is an exploded isometric view showing one of the shore columns and soffit cross means for support on the head end of the column;

20 FIG. 8 is a side elevational view of a representative cross brace assembly;

FIG. 9 is a side elevation view of a representative soffit and support therefor;

25 FIG. 10 is an exploded isometric view of an adjustable plate soffit assembly;

FIG. 11 is a vertical sectional detail view of the adjustable plate soffit in assembly with its supporting structure;

30 FIG. 12 is an illustrative elevational view demonstrating an adaptation of the system for canted deck construction;

FIG. 13 is a fragmentary sectional plan view showing an internal or re-entrant corner half cradle connection;

35 FIG. 14 is a fragmentary sectional plan view showing an external corner half cradle assembly connection;

FIG. 15 is a sectional plan view showing details of half cradle panel connecting means;

40 FIG. 16 is a fragmentary elevational view of a shore head tilt assembly;

FIG. 17 is an elevational view of the tilt assembly looking toward the right in FIG. 16;

FIG. 18 is a side elevational view of a modified displacement dome construction;

45 FIG. 19 is an isometric view exemplifying use of at least a portion of the dome structure of FIG. 18 in an inverted relation to form a ribbed floor base;

FIG. 20 is an enlarged fragmentary sectional elevational detail view taken substantially along the line XX-XX of FIG. 19;

50 FIG. 21 is a fragmentary sectional detail view taken substantially on the line XXI-XXI of FIG. 18; and

FIG. 22, is an enlarged fragmentary sectional plan view taken substantially along the line XXII-XXII of FIG. 18.

According to the present invention, a forming system is provided for concrete floor and roof deck construction, according to one embodiment of which a reusable shore assembly is erected on which reusable soffits and form members such as generally waffle pattern displacement domes are assembled and supported to complete a deck support on which a concrete slab is poured. After the concrete of the slab has set, the form members may be removed therefrom downwardly relative to the soffits for reuse, and after the concrete slab has cured sufficiently to be efficiently self-sustaining, the shore assembly is removable for reuse. Standard-

ized components are provided which are connectable by means of hook-on and latch lock connections. According to another embodiment the displacement domes 12 may be utilized in an inverted generally waffle pattern to provide a cross-ribbed concrete floor base.

In a representative form, the system includes (FIGS. 1 and 2) supporting means including vertical posts or shores 20 on which are supported form members which may be, as shown, displacement domes 21 of any desired configuration such as rectangular in plan but which may be triangular or other geometric configuration, and provided with suitably tapering sides 22 providing draft to facilitate withdrawal from a set poured concrete deck such as a floor or roof in the bottom of which the domes effect a generally waffle pattern of load-reducing recesses. Between the recesses ribs are provided in the underside of the deck between the adjacent forming domes 21 and on top of soffits 23 and soffit crosses 24 supported by the shores 20 between and complementary to the walls 22. Where a substantially uniform thickness slab is desired in the deck, flat panels may be substituted for the domes 21. For molding of a rim, perimeter ledge, eaves overhang, or the like as may be architecturally required, half cradles 25 are carried by the shores 20. All of these components of the system are separably assembled in a manner enabling quick erection and dismantling for reuse, and the various parts are interchangeably standardized.

Means are provided for detachably connecting the displacement domes 21 to the shores 20, preferably vertically adjustable to enable varying the height to which the domes project above the soffits 23 to accommodate architectural requirements for depth of displacement recesses. To this end each of the domes 21 carries on bottom frame structure 27 thereof (FIGS. 1 and 6) and extending inwardly from each corner an arm 28, attached thereto as by means of a bolted clamp 29, of a generally L-shape bar having a depending leg 30 received in a vertical sleeve 31 fixedly carried by a vertical attachment bracket bar 32 which is adapted to be removably received by one of the shores 20. Removable connection with the shore is desirably effected by means of similar, complementary downwardly facing hooks 33 and 34 at respectively the upper and lower end portions of the hanger bar and retainingly engageable with respective upper and lower coupling collars 35 and 37 fixedly carried on the shore 20. Each of the shores 20 being metal such as steel, the collars 35 may also be of similar metal and of a ring-shape larger in diameter than the shore 20 on which mounted to provide a groove for receiving the downturned terminals of the hooks 33 and 34, each of the collars being secured as by welding to its shore through an annular spacer rib 38 which is located intermediate the ends of the collar to provide substantially equal groove space above and below the rib. By having the collars 35 and 37 substantially spaced longitudinally along the shore 20 great stability is attained when the complementally spaced hooks 33 and 34 are engaged with the collars. For maintaining the dome in any preferred vertical position of adjustment, the leg 30 and the sleeve 31 are desirably provided with matching transverse pin holes 39 and 40, respectively, into which a pin such as a bolt or other type of pin 41 is adapted to be engaged, extending through respective aligned ones of the holes 39 and 40 at the desired vertical or elevational adjustment.

Means are provided for firmly maintaining the shores 20 in desired spaced relation to one another. To this end, respective upper and lower horizontal connecting brace assemblies are constructed and arranged to be connected releaseably to and between the collars 35 and 37 which are fixed in uniform, standardized relation on all of the shores. The upper horizontal brace 42 (FIGS. 2 and 9) comprises a longitudinally adjustable bar of desirably at least two telescopically joined and relatively longitudinally adjustably related bar sections 44 and 45 wherein the section 44 at least is tubular to receive the section 45, which may be either tubular or solid, telescopically through one end. Suitable means for locking the sections 44 and 45 in longitudinally adjusted relation desirably comprise a locking pin 47 which may be a bolt, but is shown as of generally L-shape with an angular handle at one end and with the shank dimensioned to extend slidably into and through registering ones of respective series of adjustment pin holes 48 and 49 in respectively the section 44 and 45 transversely in the telescopically related portions of the bar sections. Desirably, the bar sections are formed of square or at least rectangular transverse cross section, whereby the series of pin holes in the bar sections will remain in longitudinal alignment.

Each of the lower horizontal brace bars 43 (FIGS. 1, 2 and 8) comprises an assembly of telescopically related, longitudinally adjustable sections in an at least two section arrangement as described for the brace bar 42, but shown as of greater versatility and adapted to be substituted where desirable for the brace bar 42, as comprising three relatively telescopically related bar sections 50, 51 and 52. In this instance the bar section 50, at least, is of tubular transverse cross section with the sections 51 and 52 telescopically received within respective opposite ends of the section 50. All of the bar sections 50, 51 and 52 are desirably of quadrangular cross section, with spaced longitudinal series of locking pin holes 53 in the respective opposite end portions of the section 50 adapted to register with selective ones of matching pin holes 54 in the bar sections 51 and 52, with locking pins 55 of any suitable form such as bolts or otherwise headed and manipulatable pins arranged to extend through the registering pin holes to lock the bar sections in longitudinal adjusted alignment.

At each opposite end of each of the bar assemblies 42 and 43 is provided a respective attachment and locking clamp 57 by which the bar is arranged to be detachably secured to the selected attachment collar 35 or 37, as the case may be. All of the clamps 57 are desirably constructed identically and therefore a detailed description of one will apply to all. Reference is therefore invited to FIG. 5 which discloses a typical one of the clamps 57. In a desirable arrangement, the clamp 57 comprises a pair of separable jaws comprising, as shown, a lower jaw 58 and an upper jaw 59. Each of these jaws is preferably in the form of a plate having on one edge a pair of transversely coextensive finger lugs 60 projecting from the plane of the jaw body and in assembly extending toward one another on the coextensively aligned ends of the jaws whereby to enable retaining engagement with the inner margins of the collar 35 or 37 against which the jaws 58 and 59 are adapted to be clamped. In this instance, the lower jaw 58 is fixedly secured, as by means of welding 61 to the underside of an end portion of the associated bar 42 or 43.

and to extend sufficiently beyond the end of the bar to accommodate the attachment collar between the finger lugs 60 and the bar end.

To enable ready opening and closing of the clamp 57 and to facilitate movement of the clamp into or out of association with the selected attachment collar, the upper jaw plate member 59 is mounted movably on manipulating means including a vertical rod 62 to the upper end portion of which this jaw is secured as by means of welding 63 and which extends downwardly from the upper jaw through a clearance aperture 64 in the associated brace bar and through an aligned bearing hole 65 in the lower jaw plate 58. At its lower end portion, the rod extends substantially below the lower jaw and has a downwardly opening bifurcation slot 66 within which is pivotally attached as by means of a horizontally extending pivot pin 67 a flat head end portion 68 (wider than the bearing hole 65) of a manipulating handle 69. The arrangement is such that when the handle 69 is in the horizontal position shown in FIG. 5 biasing means in the form of a coiled compression spring 70 mounted about the rod 62 and thrusting at its respective opposite ends against the jaw members 58 and 59 causes the upper jaw member 59 to be raised into open clamp relation relative to the lower jaw member and to a sufficient height to clear the retaining finger lugs 60 above the upper edge of the associated collar. This facilitates placement of the clamps 57 in engaging relation to or removal from the collars 35, 37 in mounting of the respective braces 42 or 43 by swinging of the upper jaw 59 between collar-engaging and clearing relation by turning the rod 62 in its bearing 65 by manipulation of the handle 69, exemplified at the right in FIG. 11 but for illustrative purposes showing it in closed position. In mounting of the bars 42 and 43, the open upper jaws 59 of the clamps 57 at their opposite ends are turned to extend in a direction transverse to the associated bar and lower jaw 58 whereby the lower jaw of each clamp can be freely moved upwardly into engagement with the lower edge of the selected attachment collar. Then the upper jaw 59 is swung into its co-acting relation to the lower jaw 58 with the lugs 60 of the upper jaw in position to engage with the upper edge portion of the associated collar. Latching of the clamp 57 onto the associated collar is adapted to be effected by moving the handle 69 downwardly from its horizontal position to turn the head 68 about the pivot 67 and thereby thrust a cam terminal 68a on the head against the opposing surface of the jaw 58 to pull the rod 62 downwardly in opposition to bias of the spring 70 whereby the upper jaw 59 is drawn into clamping engagement with the collar. Dimensions of the parts is such that when the handle 69 is moved into vertical position the jaws 58 and 59 are in tight clamping engagement with the interposed collar and there is substantial frictional resistance to unintentional displacement of the handle 69, and more particularly the head 68 from the latching position.

While reasonably accurate spacing adjustments of the brace bars 42 and 43 can be effected by the locking pin system described, additional means are desirably provided to attain a tight adjustment and prevent undesirable looseness in the clamp and collar connections. To this end, each of the brace bars has on one end thereof a fixed threaded bar extension 71 (FIGS. 1, 2, 8 and 9) on which is threadedly adjustably engaged a clamp-carrying block 72. Through this arrangement by

turning the block 72 on the extension 71 the overall length of the associated bar is adapted to be lengthened or shortened by substantially micrometer increments. In effecting this the handle 69 of the associated clamp 57 may be employed for turning the block 72. The desired adjustment can then be locked as by means of locknuts 73 threadedly engaged on the extension 71 and drawn up tight against the adjacent end of the block 72.

Construction of the soffits 23 is such that they are adapted to be mounted on the upper brace bars 42 and thereby readily installable and removable in the system. For this purpose, each of the soffits 23 is desirably provided with means for attaching it to one of the brace bars 42, preferably in a manner to enable ready replacement of the soffit for any of various reasons such as if it becomes damaged, if a soffit of different size or configuration is needed, and the like. Representative of such means are depending bolts 74 (FIGS. 2 and 9) secured through clamping plate means 75 underlying the brace bar and fastened as by means of nuts 77. As shown, the bolts 74 extend through the brace bar, but if preferred they may comprise a pair of the bolts straddling the brace bar. Since for practical operational reasons the upper attachment collars 35 must be spaced a limited distance below the tops of the shores 20, and the soffits 23 must cooperate uniformly with the soffit crosses 24 which are mounted on the upper ends of the shores, spacer means are provided in the form of brackets such as blocks 78 under the soffit units 23 to rest on the brace bar 42 and clamped thereagainst by the bolts 74 in cooperation with the clamping plates 75. To accommodate variations in top plane of the brace bar due to different sizes of bar section, shim plates 79 may be interposed between the ends of the brackets 78 and the associated bar section where necessary. In order to enable ready mounting and dismantling of the soffits 23 relative to the soffit crosses 24, the ends of the soffits 23 are obliquely angled upwardly and inwardly as shown, enabling upward placement and downward removal relative to complementary beveled ends on the soffit crosses as is apparent in FIGS. 1 and 2. For uniform snug contact with the tapered side walls 22 of the displacement domes 21, the side surfaces of the soffits 23 are formed on complementary taper. Each of the soffits 23 may be formed as a unitary bar or as a built-up bar section, as may be preferred.

Since due to the taper of the displacement dome sides 22 different architecturally required elevations of the displacement domes will require different widths of soffit bars to fill the between-dome valley root areas, with the bar type of soffits 23 this means that sets of soffits of the required widths must be provided. Therefore, readily adjustable soffits 80 as represented in FIGS. 10 and 11 may be preferred. To this end the soffit structure 80 comprises an assembly of longitudinally coextensive plates comprising a bottom plate 81, an intermediate plate 82 and a top clamping plate 83. For securing the plates together in adjustable relation as to width of the assembly, the clamping plate is provided with a set of longitudinally spaced depending studs 84 arranged to extend downwardly through respective complementary transverse matching adjustment slots 85 and 87 in respectively the plates 82 and 81 such that by means of nuts 88 run up on the studs 84 the plates can be clamped together in any preferred relative width adjustment and with the upper imperforate clamping plate 83 effectively closing the slots 85 and 87 therebe-

low against poured concrete leakage. Along their outer edges, the soffit plates 81 and 82 are provided with respective upstanding outwardly tapering dome sidewall engaging flanges 89 which are on the same taper angle as the dome sidewalls.

Means for attaching the adjustable plate soffit 80 to its associated brace bar 42 comprise a suitable set of supporting brackets 90 which may be in the form of blocks, but are preferably, as shown, one-piece shaped sheet metal members. Each of the brackets 90 comprises a supporting head 91 provided with a stud hole 92 through which one of the studs 84 extends and thereby enables clamping of the head 91 to the underside of the lower soffit plate 81 by means of the nut 88. For attaching the bracket 90 to the brace bar, a pair of downwardly extending attachment legs 93 from the respective opposite sides of the head 91 are spaced apart to receive the brace bar therebetween and adapted to be clamped thereagainst as by means of bolts 94, there being one of the bolts above and another of the bolts below the brace bar to assure firm attachment against displacement of the bracket 90 in any direction relative to the brace bar.

Construction of the soffit crosses 24 is such as to cooperate efficiently with the respective ends of the soffits 23 or 80, as the case may be, and the corner portions of the associated displacement domes 22. To this end, as best seen in FIGS. 1, 2 and 7, the soffit crosses 24 are provided with a plurality of arms 95 which radiate from the body of the cross unit, the ends of the arms being tapered downwardly and inwardly for cooperation with corresponding complementary ends of the soffit bars, and the sides of the arms being tapered complementary to the dome wall taper. There may be as many of the arms 95 as required for the particular location in the system in which the soffit cross is to be used. Where a four soffit joint connection is to be provided by the soffit cross, then four radiating arms will be provided as shown in FIGS. 1 and 7. Where a three soffit bar joint is to be accommodated such as at an intermediate point along a side edge of the system, a three arm soffit cross will be provided as shown at the left in FIG. 1. At an outside corner of the system only two arms may be needed. More than four arms may be provided if necessary. Architectural requirements can thus be readily met by providing soffit cross modules of any multiple or relative radial arm disposition necessary.

Mounting of the soffit crosses 24 on the tops of the shores 20 is desirably in a manner to enable quick mounting and disassembly or replacement. To this end, each of the soffit crosses is provided with a fixed depending attachment pin 97 receptive in a complementary upwardly opening socket 98 in the top of the associated shore 20. In one practical form, the attachment pin 97 may be a fixed depending projection from a mounting plate 99 adapted to be secured to the underside of the soffit cross body as by means of flat head bolts 100 extending through respective aligned holes 101 and 102 in the soffit cross and the plate. Through this arrangement, mounting of the soffit cross 24 on the shore 20 is readily effected by inserting the pin 97 into the socket 98. This arrangement enables efficient adjustable accommodation of the soffit cross gravitationally with the associated displacement domes and with the respective ends of the soffit bars connected therewith.

Mounting of the half cradles 25 is also adapted to be effected on the shores 20 along the outer edges of the system by readily detachable mounting on the collars 35 and 37. For this purpose, the half cradles comprise 5 a frame and panel assembly comprising a supporting frame module 103 removably attached to each of the outer edge or boundary shores 20 and a panel 104 supported by and between the respective half cradle supporting frames (FIGS. 1, 2, 3 and 4). Each of the 10 frames 103 comprises a horizontal frame bar 105 having mounted on its inner end one of the clamp assemblies 57 by which it is detachably connectable to the upper collar 35 of the associated shore. For connecting the frame 103 to the lower attachment collar 37, a diagonal brace bar 107 extends from an intermediate portion of the bar 105 and is connected at its lower end to an integral rib 108 on a half round thrust pad which bears against the shore and has its lower end engaged in the upwardly opening groove provided by the lower collar 37 (FIG. 3), there being a take-up lug extension 110 on the lower end of the rib 108 to engage with the rim of the collar. By having the bar 107 pivotally connected to the rib 108 as by means of a bolt 111, assembly of the frame 103 is greatly facilitated because the pad or shoe 109 can be assembled with the collar 37 by an inward and downward sliding movement toward the shore and collar and then the upper portion of the frame swung in toward the shore and the clamp 57 on the bar 105 secured to the collar 35. Firm support of the frame 103 on the shoe 20 is thus effected.

For supporting the panel 104, an upwardly extending frame bar 112 is supported by the inner end portion of the base bar 105, being connected thereto by means enabling ready adjustment inwardly and outwardly relative to the associated forming structure to accommodate architectural requirements for widths of the marginal portion of the slab to be formed on the forming system. Desirable means for this purpose comprise an outwardly extending connector 113 having an inner end pivot 114 to which the lower end portion of the bar 112 is attached and provided on its inner end with a downwardly extending clevis 115 straddling the bar 105 and arranged to be lockingly attached thereto as by means of a pin or bolt 117 engaged through any selected one of a plurality of longitudinally spaced adjustment holes 118 extending transversely through the bar 105. To facilitate support and adjustment of the connector 113, a longitudinal bearing plate 119 may be provided on the upper face of the bar 105 underlying the connector. For substantially micrometer accuracy of adjustment of the lower end of the bar 112, the connector 113 is desirably provided with adjustment screw means 119a on the order of a turnbuckle or the like.

To support the frame bar 112 upright and in any preferred adjusted angular position from vertical to slanting angle as indicated by comparison of the full line position and the several dash line positions in FIG. 3, a longitudinally adjustable diagonal strut 120 connects the upper end of the bar 112 and the outer end portion of the base bar 105. For longitudinal adjustment throughout a substantial range, the strut 120 is preferably constructed of a plurality of telescopically related sections comprising a tubular lower section 121 having its lower end pivotally connected as by means of a pin or bolt 122 to the bar 105 and telescopically receiving within its upper end an intermediate tubular bar section 123 which in turn telescopically receives in its upper

end an upper bar section 124. Each of the bar sections has a longitudinal series of transverse pin or bolt holes 125 enabling numerous incremental longitudinal adjustments in length of the bar sections, with pins or connecting bolts 127 securing the respective end portions of the telescopically related bar sections together in any desired relationship of adjustment. Additional range of adjustment is afforded by having the bar 105 provided with a longitudinally spaced series of transverse pin holes 128 for receiving the connecting pin 122. At its upper end the bar section 124 is provided with means for connecting it pivotally to the upper end of the bar 112 in a manner to enable fine, substantially micrometer final adjustment in the angularity of the bar 112, and thus of the supported panel 104 relative to the horizontal. Such means desirably comprise a turnbuckle-like screw adjustment assembly 129 secured at one end to the upper end of the truss bar section 124 and having an attachment head 130 pivotally secured as by means of a bolt 131 to the upper end of the bar 112.

Attachment of the panel 104 to and between adjacent ones of the frame bars 112 is desirably effected in a manner to enable quick and easy assembly and disassembly of the components. For this purpose the frame bar 112 in each instance is desirably of angular cross section providing a pair of spaced outwardly projecting longitudinal flanges 132 (FIGS. 4 and 15), and the panel 104 has a frame 133 providing outwardly projecting flanges 134 matching the flanges 132 and adapted to be aligned in face-to-face coextensive relation therewith in assembly. To facilitate assembly, the bars 112 are provided with face plates 135 which have the respective side margins projecting a limited distance beyond the width of the bar 112 to provide seats at their outwardly or rearwardly facing surfaces receptive of the frame bars 133 which have seating areas thereof offset relative to the adjacent side edges of the panel 104 in each instance for this purpose, as best seen in FIG. 15.

Readily manipulatable locking and latch means are provided for securing the frame flanges 132 and 134 in assembly, desirably comprising locking bolts 137 rotatably and axially shiftably supported by respective bearing brackets 138 and the associated frame flange 134 and lockingly projectable through respective keeper holes 139 in the flanges 132. As shown, two of the locking bolts 137 are provided in vertically spaced relation on each of the side frame bars of the panel assembly. Each of the bolts 137 has on its inner end portion a laterally extending manipulating handle 140 by which the bolt can be manipulated both rotatably and longitudinally in its bearings. Means for retention of the bolt 137 in each instance against being inadvertently withdrawn from its bearings, and also providing a latch are provided on the locking end portion of the bolt between the bearings 138 and the flange 134. This comprises a rigidly attached latch arm 141 having a latch hook 142 which is adapted to be engaged over and about the flanges 132 and 134 when the bolt 137 has been thrown into locking relation through these flanges. Movement of the latching hook head 142 between latching and releasing positions is readily effected by turning the bolt 137 about its axis through manipulation of the handle 140. When the latch 142 is engaged with the flanges 132 and 134, inadvertent release of the bolt 137 is prevented.

To accommodate joining of the adjacent sides of respective panels 104 located at an inside or re-entrant corner of the system, a modification of the half cradle frame bar 112' as shown in FIG. 13 may be employed, wherein this frame bar has the body thereof provided with outside angularly related portions and the facing plate 135' is similarly angularly constructed. Other parts of the assembly will be the same as in the arrangement as already described and identical reference numerals have therefore been applied.

To accommodate outside corner assembly of the half cradle panels 104, the arrangement shown in FIG. 14 may be employed, wherein the frame bar 112'' has a re-entrant angular body form. For this purpose the facing plate 135'' will have a similar re-entrant angular body form. All other elements on the combination may be the same as previously described and identical reference numerals have been applied thereto.

Means are provided for setting the apparatus of the system carried by the shores 20 level on a supporting surface. To this end, individually adjustable levelling jacks 143 (FIG. 2) are provided. Each of the jacks comprises a base or foot pad 144 supporting a non-rotatable vertical screw 145 on which is threadedly mounted a capstan-like adjustment collar 147 provided with manipulating means such as radially extending handles 148. On its upper portion, the member 147 is of reduced diameter whereby to provide an upwardly projecting centering stem 149 about an upwardly facing annular bearing shoulder 150 to receive the lower end of a tubular thrust extension member 151 into which the upper end portion of the screw 145 and the stem extension 149 extend. Preferably the member 151 is held against turning relative to the screw 145 by means comprising a stud 152 projecting radially from the portion of the screw within this member and into a vertical guide slot 153. Spaced a limited head projection distance below the upper end of the member 151 is fixedly mounted one of the attachment collars 37, whereby the levelling jacks for the several shores are adapted to be secured in stable accurately spaced relation by means of respective horizontal brace members 43 in the same fashion as the lower end portions of the shores 20.

For standardization purposes, the shores 20 and the levelling jack assemblies 143 are provided in uniform lengths substantially shorter than will normally be required for ceiling heights as may be architecturally specified, to enable accommodation for the particular specified height on any construction site by simply providing intermediate shore extensions 154. These may be simply pieces of tubular stock identical with the tubular stock from which the shores 20 are made, and from which the jack extension members 151 may be made, for uniformity of compression load support. For connecting the lower ends of the shore extensions 154 to the respective jack assemblies, a generally bell socket 155 is provided on the lower end of each member 154 dimensioned to receive in telescopic supporting relation the head end portion of the jack extension 151. At its head end, the shore extension 154 is desirably of unaltered diameter and is received in supporting relation within a downwardly opening suitably enlarged bell socket 157 on the lower, foot end of the associated shore 20. Through this arrangement, the shores 20, the extensions 154 and the jack members 151 in effect provide a continuous solid shore column.

which is adjustable as to length within a wide range by interchangeability of the shore extensions 154 to suit requirements.

To meet architectural specifications for slanting or pitched roof deck slabs, means are provided enabling erection of the shores 20 in a manner to support the domes, soffits and half cradles in the required tilted attitude. To this end, respective, standardized tilt connection devices 158 (FIGS. 12, 16 and 17) are provided to enable suitable angularity in the shoring assemblies relative to a generally horizontal supporting base. Each of the assemblies 158 includes a cylindrical head portion 159 dimensioned to be received in the bell socket at the lower end of one of the head shores 20. This head portion is connected by tiltable means comprising a plate 160 to a lower portion 161 having a lower end bell socket 162 for telescopic assembled reception of the head end of one of the shore extensions 154. In a desirable construction, the tilt plate 160 is of generally segmental shape having its apical end portion pivotally secured as by means of a pin bolt 163 near the lower end of an upwardly opening diametrical slot 164 in the body portion 161. For attachment to the head portion 159, the tilt plate 160 has at least a portion, in this instance an extension 165 of suitable width projecting above the end of the body portion 161 to project into a diametrical downwardly opening slot 167 in the head portion 159 and supporting the opposed ends of the portions 159 and 161 sufficiently spaced to enable a desirable range of relative tilting adjustment by suitable rocking of the tilt plate about the pivot 163. Securement of the tilt plate extension 165 in the slot 167 is effected as by means of a plurality of bolts 168. To maintain any desired tilt adjustment within a substantial range, the tilt plate 160 is provided with a series of arcuately arranged spaced locking pin holes 169, desirably in a plurality, herein two staggered rows on a radius of the pivot 163 and spaced therefrom to receive a locking pin or bolt 170 extended through either of a pair of longitudinally spaced matching locking pin holes 171 extending through the body portion 161 and with one of which one of the pin holes 169 will register in any of the incremental tilt adjustments of the plate 160 and thus of the head portion 159 relative to the body portion 161.

To accommodate any particular tilt adjustment over a substantial span, involving a plurality of the head shores 20, graduated lengths of the intermediate shore extensions 154 are provided, and intermediate lengths 154a and a minimum or short length 154b being identified in FIG. 12. It will be understood that these graduated lengths for the intermediate shore members may be suitably graduated to accommodate a relatively long or wide roof span and that there will be as many graduated lengths as necessary for the particular building project under construction.

In order to stabilize and prevent any undesirable sway in the forming assembly where the tilted arrangement of FIG. 12 is employed, diagonally arranged brace struts 172 are desirably provided of suitably graduated lengths and comprising straight bars which are suitably connected as by means of respective screws or bolts 173 to and between the opposite end portions of the soffit-supporting transverse brace bars 42 and lower transverse brace bars 43 which may, for this purpose, be attached to attachment collars 37

mounted on the intermediate shore extensions 154, 154a and 154b adjacent to the sockets 155 thereof.

Although the displacement domes 21 will be most generally used in the forming of a waffle pattern of displacement cavities in the lower face of a poured concrete deck, those domes are adapted also for advantageously forming a grid ribbed floor base wherein the domes are mounted in inverted relation in a manner to enable forming of ribs with upwardly opening voids therebetween. For this purpose, of course, the shore structure will not be needed. However, suitable means for properly spacing the domes one from the other to determine formed rib width will be desirable.

In FIGS. 18 and 19 is depicted a form of dome 175 which is especially well adapted for either upright or inverted use and which, in addition, has adaptability for readily varying the height of the domes over and above the height variability provided for through the shore-supported vertically adjustable arm devices. Further, it may be preferred to eliminate the arm devices for some reason and thus to have the domes themselves adjustable as to height. In a practical construction to this end, each of the domes 175 is constructed in a plurality of sections which may be as many as preferred and of any preferred gradation as to height, but as shown comprises a lower section 177 and an upper section 178 as well as a top closure 179. In the illustrated instance, the dome sections 177 and 178 are shown as of equal height, and the top 179 as of only fractionally the height of the dome sections. The dome sections 177 and 178 and the top 179 are separable and may be employed independently of one another. In regular upstanding dome arrangement, the upper dome section 178 and the top 179 may be used together but separate from the lower dome section 177. On the other hand, either of the dome sections 177 or 178 may be used independently of one another and of the top 179 for inverted forming of floor rib structure. For very shallow displacements, the top 179 may be utilized as a displacement dome.

Each section of the dome 175 is adapted to be constructed from sheet metal, and for compactness in shipment and storage, at least the dome sections 177 and 178 are adapted to be constructed in a manner to enable the walls to be separably assembled. To this end, the dome section 177 comprises an assembly of similar side wall panels 180 formed from suitable gauge sheet metal and desirably provided with reinforcing ribs 181 extending in parallel spaced relation in the major dimension of the panel, in this instance in the horizontal direction. At its bottom edge, each of the panels 180 has an inturned reinforcing base flange 182. Along the upper edge of the panel is a similar inturned reinforcing head flange 183. At one end each of the panels 180 has means for cooperative interengagement with the companion panel, comprising an angularly turned flange 184 at one end extending between the flanges 182 and 183, while the opposite end has a flange 185 inset to accommodate the thickness of the flange 184 and lapingly engaged therewith in assembly as best seen in FIG. 21, being provided with an angled reinforcing flange 187. Through this arrangement, the panels 180 are adapted to be assembled at their ends in angular relation, and separable means are provided for retaining the wall panels assembled, desirably comprising connecting and corner brace bars 188 in the form of rods adapted to extend diagonally between the angularly re-

lated panels and having similarly turned coextensive angular terminals 189 arranged to fit in slidable separable connection within respective sockets 190 fixed on the inner wall surface of the respective panel, desirably aligned with the reinforcing ribs 181 for maximum rigidity. Through this arrangement, assembly of the wall panels 180 into the dome section is quickly effected by connecting the respective ends of the panels with the flanges 184 and 185 in lapping relation, and installing the connecting braces 188. Similarly, dismantling of the dome section is readily effected by pulling the connecting braces free from the sockets. Construction of the upper dome section is preferably identical with the lower dome section except that the wall panels are properly dimensioned to conform to the desired taper of the overall dome assembly when assembled with the lower dome section 177. Description of the elements of the upper dome section will be understood to be consistent with the description of the elements of the lower dome section and identical or primed reference numerals indicate similarity.

In a preferred construction, the relatively shallow dome top 179 comprises a formed sheet metal inverted pan-like structure, provided with an inturned marginal seating flange 191. In assembly, the flange 191 seats in complementary coextensive relation upon the top flange 183.

Means are provided for connecting the sections 177 and 178 and the dome top 179 together, preferably in a manner to enable quick fastening and release. To this end, bolt-latch assemblies 192 are provided which may be on the order of those by which the half cradle panels 104 are secured to the frame units 103. Each of the bolt-latches 192 comprises a bolt 193 journaled through a generally U-shaped bracket 194 which is secured as by means of welding to the inner face of the wall of the respective dome section 177 and 178 contiguous to the top flange 183, 183' thereof. For locking the dome assembly components together, the bolt 193 is of a length to project through aligned bolt holes 195 (FIG. 22) in the flange 183 or 183', as the case may be and the superimposed seating flange 182' or 191, respectively, with manipulating means such as a bolt head 197 engaging against the lower flange of the bracket 194. For latching the bolt against unintentional withdrawal; a generally U-shaped latching jaw 198 is mounted on a radial arm 199 fixedly secured to the bolt on the portion thereof extending between the spaced flanges of the bracket 194 and at such a position that when the bolt is fully lockingly engaged through the superimposed flanges of the dome members, the arm 199 will slidably engage the inner face of the upper flange of the bracket as a gauge and when the bolt is then turned by manipulation of the head 197 the arm 199 will be swung to drive the latch jaw 198 into reasonably firm clamping latching engagement with the lappingly seated flanges of the dome members. To release the bolt 193, it is turned in reverse by manipulation of the head 197 to swing the arm 199 inwardly and release and clear the latch jaw 198 from the connected flanges, so that the superimposed dome member can be lifted away. To hold the latch bolt and jaw in ready position, but with the latch jaws in a convenient clearance relation to avoid interference with ready disassembly or assembly of the dome sections, the arm 199 is adapted to drop down with corresponding dropping of the bolt until the arm 199 rests upon the lower flange of the

bracket 194, wherein the upper end of the bolt is nevertheless retained within its bearing relation to the bearing bracket, as demonstrated in the dash outline position at the upper left in FIG. 18. There may be as many of the latch assemblies 192 mounted on each wall of the respective dome sections 177 and 178 as may be necessary in view of the size or geometrical configuration of the dome section, a nicely balanced relationship being illustrated in FIG. 18 as comprising two of the latch assemblies on each wall, assuming the dome section is to be of generally square form in plan.

To enable attachment of the dome 175 to the supporting arms 28 of the shore assembly, bottom frame means such as respective plates 200 may be secured to the lower flanges 182 of the dome section 177 as by means of screws 201, for which the flanges are provided with screw holes 202.

For use of the dome 175 in constructing a poured concrete rib grid, an inverted mounting of as much of the respective dome assemblies as necessary to provide the depth of ribs to be produced is effected on suitable base 203 (FIG. 19) which may comprise ground level of sufficient firmness to support the structure to be built, the bottom of an excavation, or the like. By way of example, use of the bottom dome section 177 is illustrated. A suitable number of the dome sections is provided in inverted relation and with the respective adjacent dome sections maintained in suitable spaced relation to provide the widths of tapered rib section desired. Simple and convenient spacer and connecting means comprise bars 204 (FIGS. 19 and 20) of a length to span across and extend at their opposite ends sufficiently beyond the inner edges of the dome section flanges 182 to receive the upper end portions of respective connecting pins 205 which have lower inset mounting terminals 207 received in respective strap sockets 208 welded onto the inner faces of the respective walls 180 similarly as the connecting brace sockets 190. Through this arrangement it is a simple matter to slip the terminals 207 into the sockets 208 and then mount the bars 204 by receiving the upper end portions of the pins 205 in respective pin holes 209 provided in the end portions of the bars.

Where the dome sections 177 are employed in the manner shown in FIG. 19, the brace bars or rods 188 may conveniently be inserted in the normally lower ends of the strap sockets 190 which in the inverted relationship are the upper ends of the sockets, as shown. Further, by having the pin sockets 208 mounted adjacent to the sockets 190, and of the same dimensions, the terminals 189 of the brace bars 188 are adapted to be received in the sockets 208 with equal facility. This facilitates removal of the sections 177 after the formed concrete rib structure has set, enabling semicollapsibly moving the respective wall panels 180 inwardly relative to one another to the extent permitted by shifting the brace bar terminals at one end of the brace bars from its socket 190 into the adjacent socket 208. Thereby the dome sections 177 can be handled as a unit for installation at another portion of the building site for repetition of its use in the inverted relationship, without necessitating complete disassembly and then rebuilding of the sections unless to conserve space for transportation to another site it may be desirable to effect complete collapse so that the wall panels can be stacked one on another.

In any form of the invention, after the forming means have been set up, customary procedures involving setting of reinforcing steel, pipes, ducts and the like are effected and then the concrete poured into the forms and permitted to set, whereafter the forms are removed. The system enables supporting columns to be mounted either in prefabricated form or to be cast in situ together with the poured concrete deck on the forms.

It will be understood that variations and modifications may be effected without departing from the spirit and scope of the novel concepts of this invention.

We claim as our invention:

1. Forming system apparatus for poured concrete structures, comprising:

prefabricated shores mounted in spaced relation to one another;

means releasably connecting the shores in said spaced relation;

prefabricated form members releasably mounted on and between said shores;

prefabricated soffits releasably mounted on the shores in gap-closing relation to said form members and enabling a poured concrete deck on said form members and said soffits;

upstanding half-cradles releasably mounted on said shores in cooperative spaced relation to certain of said form members to provide an upwardly opening recess for forming an edge of the poured concrete deck therein;

soffits releasably mounted in gap-closing relation to said certain form members and said half-cradles in the bottom of said recess;

said form members, said soffits, said shores, said half-cradles and said connecting means being releasable and removable from one another and the deck for reuse after the concrete has set;

said half-cradles comprising supporting frame units with a panel supported by and between said units;

means for detachably mounting said frame units on respective ones of said shores;

said respective ones of the shores having thereon vertically spaced supporting collars;

and said means for detachably mounting the frame units comprising upper and lower attachment devices carried by the frame units engaged within said collars, one of said attachment devices comprising a releasable clamp gripping one of said collars and the other of said devices comprising a lug extending into the collar associated therewith and said clamp and said lug thereby cooperating to secure the frame units releasably to the shores.

2. Forming system apparatus for poured concrete structures, comprising:

prefabricated shores mounted in spaced relation to one another;

means releasably connecting the shores in said spaced relation;

prefabricated form members releasably mounted on and between said shores;

prefabricated soffits releasably mounted on the shores in gap-closing relation to said form members and enabling forming a poured concrete deck on said form members and said soffits;

upstanding half-cradles releasably mounted on said shores in cooperative spaced relation to certain of

said form members to provide an upwardly opening recess for forming an edge of the poured concrete deck therein;

soffits releasably mounted in gap-closing relation to said certain form members and said half-cradles in the bottom of said recess;

said form members, said soffits, said shores, said half-cradles and said connecting means being releasable and removable from one another and the deck for reuse after the concrete has set;

said half-cradles comprising supporting frame units with a forming panel supported by and between said units;

means for detachably mounting said frame units on respective ones of said shores;

said frame units having facings providing lateral flanges;

said forming panel having a marginal backing frame projecting laterally beyond the edges of the forming panel and engaging in back of said lateral flanges with said facing and the forming panel together presenting a coplanar forming surface;

and releasable latching means carried by said panel frame and detachably engaging with the frame units to secure said forming panel to said frame units and permitting detachment of the forming panel from the frame units and movement rearwardly relative to a set poured concrete structure and away from said lateral flanges when disassembling the associated half-cradle from the concrete structure.

3. Forming system apparatus for poured concrete structures, comprising:

prefabricated shores mounted in spaced relation to one another;

means releasably connecting the shores in said spaced relation;

prefabricated form members releasably mounted on and between said shores;

prefabricated soffits releasably mounted on the shores in gap-closing relation to said form members and enabling forming a poured concrete deck on said form members and said soffits;

upstanding half-cradles releasably mounted on said shores in cooperative spaced relation to certain of said form members to provide an upwardly opening recess for forming an edge of the poured concrete deck therein;

soffits releasably mounted in gap-closing relation to said certain form members and said half-cradles in the bottom of said recess;

said form members, said soffits, said shores, said half-cradles and said connecting means being releasable and removable from one another and the deck for reuse after the concrete has set;

said half-cradles comprising supporting frame units with a panel supported by and between said units;

means for detachably mounting said frame units on respective ones of said shores;

and said frame units comprising upright bars having opposite side marginal flanges for attachment of said panel to either of said flanges and another similar panel to the other of the flanges, said bars being angular along longitudinal lines whereby to accommodate angular disposition of the panels relative

to one another at a corner of the poured concrete deck.

4. Forming system apparatus for poured concrete structures, comprising:

prefabricated shores mounted in spaced relation to 5
one another;

means releasably connecting the shores in said
spaced relation;

prefabricated form members comprising domes hav-
ing upwardly and inwardly sloping sides;

said domes and said shores having cooperatively re-
lated means thereon releasably supporting said
domes on and between said shores;

prefabricated soffits releasably engaging in gap-
closing relation with the sloping sides of adjacent 15
ones of said domes;

means on said soffits and on said shores releasably
attaching said soffits to the shores independently
of said domes;

means for releasably supporting the domes on said 20
shores independently of said soffits;

whereby the supporting means for said domes can be
readily separated from said shores and the domes
removed downwardly relative to the soffits and the
shores;

said soffits being selectively adjustable in width and
comprise assemblies of elongated coextensive
overlapping and relatively laterally adjustable
plates;

and means for securing the plates in adjusted soffit
width relationship.

5. Forming system apparatus for poured concrete
structures, comprising:

prefabricated shores mounted in spaced relation to
one another;

means releasably connecting the shores in said
spaced relation;

prefabricated form members comprising domes hav-
ing upwardly and inwardly sloping sides;

said domes and said shores having cooperatively re-
lated means thereon releasably supporting said
domes on and between said shores;

prefabricated soffits releasably engaging in gap-
closing relation with the sloping sides of adjacent 45
ones of said domes;

means on said soffits and on said shores releasably
attaching said soffits to the shores independently
of said domes;

means for releasably supporting the domes on said
shores independently of said soffits;

whereby the supporting means for said domes can be
readily separated from said shores and the domes
removed downwardly relative to the soffits and the
shores;

said means for releasably attaching the soffits com-
prising respective attachment collars on said
shores;

said soffits having attaching bars extending length-
wise thereunder;

and jaw latch assemblies carried by end portions of
said bars and releasably engaging said collars.

6. Forming system apparatus for poured concrete
structures, comprising:

prefabricated shores mounted in spaced relation to 65
one another;

means releasably connecting the shores in said
spaced relation;

prefabricated form members comprising domes hav-
ing upwardly and inwardly sloping sides;

said domes and said shores having cooperatively re-
lated means thereon releasably supporting said
domes on and between said shores;

prefabricated soffits releasably engaging in gap-
closing relation with the sloping sides of adjacent
ones of said domes;

means on said soffits and on said shores releasably
attaching said soffits to the shores independently
of said domes;

means for releasably supporting the domes on said
shores independently of said soffits;

whereby the supporting means for said domes can be
readily separated from said shores and the domes
removed downwardly relative to the soffits and the
shores;

said means for releasably attaching the soffits to the
shores comprising respective longitudinally adjust-
able brace bars;

and releasable securing means on ends of said bars
engaging with means on the shores.

7. Forming system apparatus for poured concrete
structures, comprising:

prefabricated shores mounted in spaced relation to
one another;

means releasably connecting the shores in said
spaced relation;

prefabricated form members comprising domes hav-
ing upwardly and inwardly sloping sides;

said domes and said shores having cooperatively re-
lated means thereon releasably supporting said
domes on and between said shores;

prefabricated soffits releasably engaging in gap-
closing relation with the sloping sides of adjacent
ones of said domes;

means on said soffits and on said shores releasably
attaching said soffits to the shores independently
of said domes;

means for releasably supporting the domes on said
shores independently of said soffits;

whereby the supporting means for said domes can be
readily separated from said shores and the domes
removed downwardly relative to the soffits and the
shores;

and said soffits comprising elongated bars having
slanted ends cooperating with complementary
slanted ends of other soffits in the assembly.

8. Forming system apparatus for poured concrete
structures, comprising:

prefabricated shores mounted in spaced relation to
one another;

means releasably connecting the shores in said
spaced relation;

prefabricated form members comprising domes hav-
ing upwardly and inwardly sloping sides;

said domes and said shores having cooperatively re-
lated means thereon releasably supporting said
domes on and between said shores;

prefabricated soffits releasably engaging in gap-
closing relation with the sloping sides of adjacent
ones of said domes;

means on said soffits and on said shores releasably
attaching said soffits to the shores independently of
said domes;

means for releasably supporting the domes on said
shores independently of said soffits;

whereby the supporting means for said domes can be readily separated from said shores and the domes removed downwardly relative to the soffits and the shores;

said soffits comprising elongated bars having end portions spaced from one another at opposite sides of vertical axes of the shores; and fill-in soffits mounted on top of said shores and connected to and between said spaced ends of the elongated soffit bars.

9. Apparatus according to claim 8, wherein said soffit bars are disposed in right angular relation to one another and said fill-in soffits having angular arm portions engaging the ends of said bars.

10. Apparatus according to claim 8, wherein said elongated soffit bars are located in angular relation to one another with four of the elongated bars having ends thereof spaced from one another and the axis of a shore, and said fill-in soffits comprise cross-shaped members having respective arms extending to and engaging with the respective ends of said elongated soffit bars.

11. Prefabricated forming system apparatus for poured concrete deck structures, comprising: domed form members, soffits between the form members and, shores supporting the form members and soffits, and all connected together releasably and removably from one another and a completed concrete deck for reuse, including:

vertically elongated shore posts; each shore post having a collar adjacent to its upper end and another collar adjacent to its lower end and said collars having axially opening grooves therein; means removably engaging in the grooves in both of the collars of the shore posts and thereby removably supporting the dome members on the shore posts; and

supporting bars mounting the soffits and extending between spaced ones of the shore posts and having releasable clamps engaging retainingly within the grooves of the upper of the collars.

12. Apparatus according to claim 11, wherein the upper collars have axially opening grooves on axially opposite sides so that each of such collars has an upwardly opening groove and a downwardly opening groove, and said clamps comprising jaw clamps engaging in both of the grooves of the upper collars and having manually operable handles for effecting engagement and release of the clamps relative to the upper collars.

13. Apparatus according to claim 12, said clamps each comprising a lower jaw and an upper jaw, a connecting rod slidable through the lower jaw and carrying the upper jaw, a spring normally biasing the jaws apart, and the handle being pivotally mounted on a portion of the rod extending below the lower jaw and having a cam portion bearing against the lower jaw to draw the upper jaw toward the lower jaw in clamping relation to the associated upper shore collar.

14. Apparatus according to claim 11, said means connecting the dome members to the collars of the shores comprising detachable brackets having vertical portions engaging in said grooves of the upper and lower collars, and means detachably securing the dome members to said brackets.

15. Apparatus according to claim 14, said brackets having vertical sleeves, said means attaching the dome

members to the brackets comprising downwardly extending legs received in said sleeves, and means for vertically adjustably securing said legs in the sleeves.

16. Apparatus according to claim 11, wherein said attaching means on the dome members comprise bars secured to the undersides of the dome members and having downwardly extending portions removably engaged with said brackets.

17. Apparatus according to claim 16, said brackets comprising vertically extending bars, and attachment hooks on respective opposite ends of the bars detachably engaging within said grooves of the collars.

18. Apparatus according to claim 11, wherein said means attaching the dome members to said brackets are removable from the dome members whereby the dome members may be employed in inverted position in a ground-supported relation to form a poured concrete grid rib floor base.

19. Forming system apparatus for poured concrete structures, comprising:

prefabricated shores mounted in spaced relation to one another;

means releasably connecting the shores in said spaced relation;

prefabricated form members comprising domes having upwardly and inwardly sloping sides;

said domes and said shores having cooperatively related means thereon releasably supporting said domes on and between said shores;

prefabricated soffits releasably engaging in gap-closing relation with the sloping sides of adjacent ones of said domes;

means on said soffits and on said shores releasably attaching said soffits to the shores independently of said domes;

means for releasably supporting the domes on said shores independently of said soffits;

whereby the supporting means for said domes can be readily separated from said shores and the domes removed downwardly relative to the soffits and the shores;

said soffits comprising bars located along lines which extend angular to one another;

adjacent ends of said bars being spaced from one another and from a vertical axis of a shore, said ends having oblique end joining surfaces;

and soffit crosses mounted over the end of the shore and having arms provided with oblique end joining surfaces complementary to and joined with said end joining surfaces of the bars.

20. In prefabricated forming system apparatus for poured concrete structure, comprising form members aligned in a common forming plane, soffits and shores connected together releasably and removably relative to one another and to concrete structure formed thereon after the concrete has set;

said shores comprising longitudinally aligned sections;

top sections of the shores extending normal to said forming plane and supporting said form members and said soffits;

means adjustably connecting said top sections of the shores in tilted angular relation to lower straight vertical shore sections for tilted forming disposition of said forming plane;

and said lower forming sections being of graduated length to facilitate the tilted forming disposition of said forming plane.

21. Forming system apparatus for poured concrete structures, comprising:

prefabricated shores mounted in spaced relation to one another;
means releasably connecting the shores in said spaced relation;
prefabricated form members having downwardly extending attachment legs;
vertically extending brackets having upwardly opening sockets;
said forming member legs telescopically received in said sockets;
means releasably securing said brackets on said shores under said form members and with the upper ends of the brackets spaced below a predetermined forming height of said form members to permit dropping of the form members from the forming height by downward telescoping of said legs into the sockets and then releasing the brackets and thereby the form members from the shores;

and releasable means for retaining the forming member legs in vertically adjusted relation in said sockets.

22. Apparatus according to claim 21, wherein said shores have vertically spaced collars with upwardly opening annular grooves therein, said brackets having respective downwardly opening hooks removably engaging on said collars and extending into said grooves and thereby facilitating removability of the brackets and dome members relative to said shores.

23. Prefabricated forming system apparatus for poured concrete deck structures, comprising form members, soffits, and vertical shores supporting the form members and soffits and all connected together releasably and removably relative to one another and to a formed deck for reuse after the concrete has set, comprising:

shore posts;
vertically spaced collars on each of the shore posts, and said collars having upwardly and downwardly opening annular grooves in their axially facing sides;
means supporting the dome members and the soffits on upper portions of the shore posts; and
brace bars extending to and between the upper and lower collars of spaced shore posts and having on the opposite ends of the brace bars respective jaw clamps engaging said collars within said grooves and including latch devices for opening and closing the clamp jaws manually.

24. Apparatus according to claim 23, wherein said brace bars comprise upper and lower horizontal brace bars, and means mounting said soffits on the upper of said brace bars.

25. Apparatus according to claim 23, said brace bars comprising telescopically related and longitudinally adjustable elements, one of said elements including micrometer longitudinal adjustment means.

26. Apparatus according to claim 23, wherein said

shore posts have respective bell-shaped lower ends, and shore extension members received in said bell-shaped lower ends.

27. Apparatus according to claim 26, said extensions having oppositely grooved collars thereon, and brace bars extending between said extension collars and having releasable jaw clamps engaging in the grooves of said extension collars.

28. Apparatus according to claim 27, said extensions having lower end adjustable jacks.

29. Apparatus according to claim 23, wherein said shore posts have upwardly opening sockets, and said soffits include members having downwardly extending attachment stems engaged in said sockets.

15 30. Apparatus according to claim 20, wherein said means for tiltably adjusting include a tilt plate pivoted on one of said shore sections and fixedly secured to the other of said shore sections, and means for adjustably securing the tilt plate relative to the shore section on which it is pivoted.

20 31. Apparatus according to claim 30, wherein said plate is of generally sector shape and has a plurality of apertures therein, said one of said shore sections having a slot within which said plate is pivotally movable, and pin means extending across said slot and through a selected one of said apertures.

32. Forming system apparatus for poured concrete structures, comprising:

prefabricated shores mounted in spaced relation to one another;
means releasably connecting the shores in said spaced relation;
prefabricated form members releasably mounted on and between said shores;
prefabricated soffits releasably mounted on the shores in gap-closing relation to said form members and enabling forming a poured concrete deck on said form members and said soffits;
means for tiltably adjusting said shores for tilted forming of the deck comprising relatively tiltable shore portions;
a tilt plate pivoted on one of said shore portions and fixedly secured to the other of said shore portions; and means for adjustably securing the tilt plate relative to the shore portion on which it is pivoted;
said form members, said soffits, said shores and said connecting means being releasable and removable from one another and the deck for reuse after the concrete has set.

33. Apparatus according to claim 32, including brace members extending to and between said shore portions, and means releasably securing the braces to said shore portions.

34. Apparatus according to claim 32, at least certain of said shore portions being of graduated lengths.

35. Apparatus according to claim 2, wherein each of said frame units includes a frame bar having a vertical flange, said panel back frame having side marginal flanges, and said latching means comprising locking bolts and associated retaining clamps and operative to secure said frame bar flanges and panel marginal flanges releasably in assembly.
